DESIGN FOR A BIRDSEED CUP

March E. Nagle, Chicago Heights, Ill., assignor to
Kimble Glass Company, Vineland, N. J., a cor-
poration of Illinois

Application March 15, 1940, Serial No. 90,971

Term of patent 14 years

To all whom it may concern:

Be it known that I, March E. Nagle, a citizen of the United States of America, residing at Chicago Heights, in the county of Cook and State of Illinois, have invented a new, original, and ornamental Design for a Birdseed Cup, of which the following is a specification, reference being had therein to the accompanying drawing, forming a part thereof, in which

Fig. 1 is a front view of the birdseed cup showing the new design;

Fig. 2 is a side view of the birdseed cup; and
Fig. 3 is a bottom view of the birdseed cup.

I claim:

The ornamental design for a birdseed cup, substantially as shown.

MARCH E. NAGLE.
